UNITED STATES PATENT OFFICE

156,020

DESIGN FOR A HARD-SURFACED RUG

Angelo P. Macchi, Walpole, Mass., assignor to Bird & Son, inc., East Walpole, Mass., a corporation of Massachusetts

Application August 25, 1948, Serial No. 148,298

Term of patent 14 years

(Cl. D92—17)

To all whom it may concern:

Be it known that I, Angelo P. Macchi, a citizen of the United States, residing at Walpole, in the county of Norfolk and Commonwealth of Massachusetts, have invented a new, original, and ornamental Design for a Hard-Surfaced Rug, of which the following is a specification, reference being had to the accompanying drawing, forming a part thereof.

The figure is a plan view of a hard-surfaced rug, showing my new design.

I claim:

The ornamental design for a hard-surfaced rug, as shown.

ANGELO P. MACCHI.
